[57] CLAIM

The ornamental design for a projection lamp reflector, as shown and described.

DESCRIPTION

FIG. 1 is a front perspective view of a projection lamp reflector illustrating our new design;

FIG. 2 is a front elevational view thereof;

FIG. 3 is a side elevational view thereof; and

FIG. 4 is a top plan view thereof.

The characteristic features of our design reside in the reflecting facets and spaced reflecting stripes on the internal surface of the reflector, it being understood that the facets and stripes are visible from the exterior of the reflector because of the relative frequency of the material from which it is made.

The bottom view of the reflector (opposite the top view in FIG. 4) not shown in the accompanying Drawings, is substantially identical to the top view in FIG. 4. The side view of the reflector opposite the side view in FIG. 3, and also not shown in the accompanying Drawings, is substantially identical to the side view in FIG. 3. The lamp member illustrated in phantom in FIGS. 1 and 2 is for illustrative purposes only and does not constitute part of the reflector herein.

FIG.1

FIG.2

FIG. 3

FIG. 4
